UNITED STATES PATENT OFFICE.

CARL ALBERT ROEPKE, OF MANCHESTER, ENGLAND.

MUSICAL BOX.

SPECIFICATION forming part of Letters Patent No. 443,114, dated December 23, 1890.

Application filed June 3, 1890. Serial No. 354,105. (No model.) Patented in England April 22, 1890, No. 6,077.

To all whom it may concern:

Be it known that I, CARL ALBERT ROEPKE, a subject of the Emperor of Germany, residing at Manchester, England, have invented 5 new and useful Improvements in Musical Boxes, (for which a patent has been granted to me in Great Britain, No. 6,077, bearing date April 22, 1890,) of which the following is a specification.

10 The improvements relate to musical boxes, and have for their object the changing of the tunes therein with facility and the general cheapening of the cost of construction thereof. To accomplish this and to effect my improvements, I provide what is known as the "comb," or row of vibrating tongues, of the ordinary description, or substitutes therefor, or additions thereto, mounted on a suitable frame, as is well understood. Instead, however, of operating this comb or the like by means of a 15 barrel formed with spikes or projections, I operate such comb by means of a traveling band or sheet of perforated card-board, paper, or other substance, through special intervening apparatus, which intervening apparatus, with the mode of action thereof, constitutes the essential part of my invention. This intervening apparatus consists of a number of 20 dual or compound levers, one arrangement 25 for each of the tongues of the comb and placed in line therewith, each being capable of receiving at the striking-point a compound motion by means of the direct pressure from the edges of the traveling perforated sheet. 30 Each principal lever turns on a fulcrum, and is formed, by preference, with two legs. It is provided at the end of the leg next the comb with a small point or projection which is capable of being caused to advance and recede 35 to and from the vibrating note of the comb on pressure from the edges of the perforated sheet being applied to the secondary or other leg attachment of the lever. The lever may 40 be held in position by means of a spring or springs or counterbalance weight or weights, or both; but by preference I employ a spring or springs for this purpose. At the end of the 45 opposite leg of the main or principal lever is fulcrumed a second short lever or equivalent 50 therefor, which is shaped at one end so as to enter the perforations in the sheet as they present themselves thereto, and as the sheet is

drawn over the same by suitable mechanism the perforations permit of the levers taking their normal or non-operating position. In 55 the preferential form of lever, as the card-board or other sheet travels forward the edges of the perforations first press back the end of the short lever, which is fulcrumed upon the principal one, and thus operates a draw-rod 60 attached to the other end, such draw-rod passing through a small hole in a projection at the end of the principal lever, by which means the point of the draw-rod is forced past the vibrator of the comb, when further pressure 65 of the edge of the perforation operates the longer lever and thereby produces the necessary sound. It is apparent that if the end of a simple lever is forced past a comb-point it will not be able to return to the first position. 70 Hence the function of the secondary lever or equivalent action is clearly seen, which is to enable the striking-point to be drawn back clear of the comb, so as to allow the lever to resume its original position as soon as a new 75 perforation presents itself; but that the invention may be better understood I will, by the aid of the accompanying drawings, proceed more fully to describe means employed by me. 80

In the drawings, Figure 1 shows a plan with the perforated sheet in operation, and Fig. 2 a plan with the perforated sheet removed, and Fig. 3 a transverse section of apparatus arranged in accordance with my invention, 85 while the remaining figures show transverse sections of modified arrangements which are obtainable by altering the position of the perforated sheet and the shape of the levers, producing the necessary compounded motion. 90

The same letters indicate corresponding parts wherever they occur.

a is the comb or row of vibrating tongues or notes of a musical box, and *b* the sheet of perforated paper. 95

c c are the primary levers, and *d d* the secondary levers at the end thereof, and *e e* and *e' e'* are the springs, while *f f* is the draw-rod, which may either be provided with a dead-stop, as at *f'*, or such dead-stop may be upon 100 the lever or levers, as will be well understood.

g g are dampers, which may or may not be employed.

x x is a bar, by preference hinged at one

end, as shown, for holding the perforated sheet in position, and *h h* is the ordinary clock-work-driving apparatus which causes the perforated sheet to travel; but this may 5 be accomplished by hand power, by means of a crank-handle, or otherwise operating the wheels which draw forward the perforated sheet.

In lieu of a comb, or in conjunction therewith, bells, drums, and other percussion sounders may be employed.

The mode of operation is as follows: The sheet is drawn forward by manual or automatic action by means of the toothed wheels 15 *jj* on the revolving shaft *k k* taking into the holes or slots formed near the edges of the sheet or at other convenient parts thereof, until the short lever ends at *d'* enter perforations made for the production of sound. 20 When the end of a lever enters into and while it remains in such a perforation, the lever is kept in its normal or inoperative position with the lever-leg *c'* resting underneath or on the striking side of the vibrator-rod of the 25 comb. As the sheet travels forward the edge of the perforation presses the short lever-leg *d'*, and the opposing leg *d''* pushes forward the draw-rod *ff*, when, on the short lever coming to its dead-stop, the further pressure 30 of the perforated sheet operates the main lever and the end of the draw-rod is forced past the comb-point, and so vibrates the same. During the time the sheet presents a blank space to the lever-leg *d'* it is retained in the 35 last-named position, as shown by the dotted lines; but on another perforation presenting itself the short lever is first released and then the main lever resumes its original place, when the operation may be repeated. 40 The end of the draw-rod or equivalent can pass the comb-point on the lever returning to its original position without difficulty and without striking the same, on account of the compound motion given to such end of the 45 draw-rod or equivalent, by fulcruming one lever upon another, whereby the to-and-fro motion of the end or point is obtained.

The arrows in each case illustrated indicate the direction of motion of the traveling 50 perforated sheet.

Variations in detail may be made—such as the shape and proportions of the levers, the direction of the two legs, and the consequent position and direction of travel of the perforated sheet, with other variations—without departing from the peculiar character of the invention. Examples of such variations are shown in Figs. 4, 5, and 6. In Fig. 4 the draw-rod *ff* is caused to slide on a separate pin, instead of through or on the opposing leg of the main lever. In Fig. 5 the short lever *d d* is placed at the acting end of the main lever *c c* and the striking-point is formed upon the end of the short lever in lieu of the longer draw-rod, while in Fig. 6 the draw-rod *ff* is linked

to the main lever *c c*. In each and every case the arrangement of levers and springs gives the end of the rod or lever forming the striking-point a compound motion, wherein it is first caused to approach the vibrating rod; 70 secondly, to be forced past the same; thirdly, to be withdrawn therefrom, and, lastly, to fall back to its original position, all of which motions are obtained solely by the pressure and release derived from the edge of the perforation in the traveling sheet acting upon the projecting end of the first lever. 75

I am aware that perforated sheets have been used, in conjunction with other intervening mechanisms, for the purpose of operating musical instruments, both of the vibratory kind and for wind-instruments; but such intervening mechanisms are different from the compound or dual levers forming this my present invention, which latter utilizes the onward 85 thrust of the edges of the perforations of the sheet for the dual purpose of putting the ends or points of the striking levers in gear, and also of causing the tongues to be vibrated by the direct action of such ends or points 90 through the intervention of reciprocating mechanism of the peculiar character indicated, by which means I obtain a simple, direct, reliable, and cheap mechanism, having small and easy action, for the construction of 95 musical boxes of the description already referred to.

Although I have described and shown in the drawings a musical box, arranged according to my invention, employing endless bands of 100 perforated card, it will be obvious that other forms of musical boxes may be constructed, wherein the improvements may be applied to the employment of perforated disks or the like.

Having now particularly described and ascertained the nature of my said invention and in what manner the same is to be performed, I declare that what I claim is—

1. In musical boxes of the character indicated, the lever *c c*, combined with the draw-rod *ff* and secondary lever *d' d''*, directly operated by the pressure of the edges of the perforations in a traveling sheet, giving the compound motion to the striking end or point, 110 and of the draw-rod *ff*, for the purpose and in manner as herein shown and described.

2. In musical boxes of the character indicated, the lever *c c*, combined with the secondary lever *d' d''*, having thereon a withdrawable striking end or point directly operated by the pressure of the edges of the perforations in a traveling sheet, giving the compound motion to such end or point, for the purpose and in manner as herein shown and 125 described.

CARL ALBERT ROEPKE.
